UNITED STATES PATENT OFFICE.

HENRY FOSBURGH, OF HOWARD CITY, MICHIGAN.

BED-SPRING.

SPECIFICATION forming part of Letters Patent No. 256,431, dated April 11, 1882.

Application filed December 14, 1881. (No model.)

To all whom it may concern:

Be it known that I, HENRY FOSBURGH, a citizen of the United States, residing at Howard City, in the county of Montcalm and State of Michigan, have invented certain new and useful Improvements in Springs, (spiral,) of which the following is a specification, reference being had therein to the accompanying drawings.

10 My invention relates to springs for beds or sofas, the arrangement of which will be fully set forth hereinafter.

In the drawings, Figure 1 is a side elevation, and Fig. 2 is a top plan view, of my 15 spring secured to the slat A by the clamping-arms b, formed upon their lower end and adapted to embrace the slat, as shown.

A is a bed-slat. B is the spring. It consists of the spirals or coils B, the wires being 20 continuous and forming a bed or plate, C, between said coils, as shown. The wire plate C is formed by carrying the wire from one of the coils—say the right-hand one—to the point e, turning it back upon itself and car-

rying it slightly curved to the point d, turning it again upon itself, carrying it to the point e, then back again to f, then to g, and from thence curving it into the left-hand coil B, as shown. This will form an M-shaped plate between the coil, which will give the 30 coils greater strength and will afford a broader spring-surface for the mattress to rest upon.

What I claim is—

In a bed-spring, in combination with the slat A, the twin springs B B, having formed between them the wire plate C, consisting of the central tongue, e, and supporting-wires c d and f g, said springs being further provided with clamping-arms b b upon their lower ends, adapted to embrace the slat and secure the 40 springs thereto, substantially as shown and described.

In testimony whereof I affix my signature in presence of two witnesses.

HENRY FOSBURGH.
